UNITED STATES PATENT OFFICE.

GEORGE E. SHAW, OF CINCINNATI, OHIO.

HAIR-CLEANING COMB.

1,159,424.

Specification of Letters Patent.

Patented Nov. 9, 1915.

Application filed February 5, 1914. Serial No. 816,755.

To all whom it may concern:

Be it known that I, GEORGE E. SHAW, a citizen of the United States, residing at Cincinnati, in the county of Hamilton and 5 State of Ohio, have invented certain new and useful Improvements in Hair-Cleaning Combs, of which the following is a specification.

My invention relates to the general class 10 of toilet articles designated as combs. One of its objects is to provide an implement for more perfectly cleaning the hair.

Another object is to provide an implement to remove the excess of natural oil 15 from the hair without injuring the hair or altering the nature of or removing the normal or requisite amount of natural oil.

Another object is to provide an improved 20 implement capable of securing improved general and individual sanitary conditions.

My invention also comprises certain details of form, combination and arrangement, all of which will be fully set forth in 25 the description of the accompanying drawings, in which;

Figure 1 is a side elevation of my improved implement. Fig. 2 is an enlarged 30 sectional detail on line *v v* of Fig. 1. Fig. 3 is a perspective view of a portion of my im- 35 proved implement.

The human hair is exteriorly rough or barbed, and being charged with natural oil, rapidly accumulates upon its exterior a quantity of dust, germs, lint, and similar 40 substances, which adhere thereto, and which the highly polished and non-absorbent combs heretofore in use fail to detach or remove. The natural oil of the hair is usually secreted in excess, and the practice 45 has been to remove it from time to time by saponification, which changes its chemical nature and results in its being removed entirely, or to an excessive degree, or if left to any extent, being in an undesirable and injurious form or state. Also it has been 50 quite common practice heretofore for two or more persons to make use of a single comb, thereby facilitating the transfer of germs and contagious diseases from one person to another. All of these objectionable features 55 are obviated by the use of my improved implement.

The accompanying drawings illustrate 55 the preferred embodiment of my invention, which comprises a comb which may be con-

structed of wood or other material to provide teeth having a fine pile or soft velvety surface as distinguished from a polished surface, and caused by the projection of a multiplicity of fine fibers. The material from 60 which the comb is to be formed may be a fibrous material of artificial production, or such as found in certain natural wood growth, of which hard maple is an example. This fibrous material after being put into 65 comb form, may by mechanical or chemical treatment or a combination of both be partially disintegrated at or near the surface of the teeth causing the free ends of a multiplicity of fibers to extend outwardly from 70 the surfaces of each comb tooth to form a delicate brush like surface. This fibrous surface upon the teeth of the comb serves to enmesh the foreign particles adhering to the hair, and to detach and remove them, 75 thereby cleaning the hair and rendering it glossy and fluffy. The teeth are also of an absorbent nature or texture, which results in any excess of natural oil being absorbed by the comb and removed from the hair 80 without removing the normal quantity of natural oil requisite to maintain the hair in proper condition, and without changing the chemical nature of the oil remaining in the hair.

When an artificially constructed fibrous material is employed the comb may be shaped integrally, that is, with the back and teeth in one piece. When produced from a natural wood growth, the comb is preferably 90 constructed of two sections of wood tongue and grooved together. The grain of the wood in section B is preferably parallel to the teeth D. The section H is also preferably of wood with the grain lengthwise of 95 the comb or at right angles to the teeth D. Section H may if desired be of material other than wood. The section B is preferably shaped into a tongue E at its edge opposite to the teeth D, which tongue is fitted 100 into a counterpart groove F in the section H, and firmly united thereto. The respective sections B and H may either or both be composed of a single piece of wood or of two or more pieces built up or united together.

Combs such as herein disclosed can be constructed at such small original cost as to enable them to be discarded or destroyed after a single use, and are designed to be 110

furnished in hotels, sleeping cars and other public places tightly sealed in original packages, thereby guaranteeing to the user their sanitary condition. The continued use of such combs keeps the hair clean, and renders it soft and glossy and of the desired texture, and keeps it in healthy condition with relatively less frequent shampooing thereof.

10 The faces 2 and 3 on the comb provide desirable spaces for advertising matter, and also directions for its use, and the proper care of the hair. The use of advertising matter on the comb serves to reduce the first cost of the comb to the consumer and thereby to enable the user to quickly discard the comb and replace it with a fresh clean one.

15 The implement herein illustrated and described is capable of considerable modification without departing from the principle of my invention.

20 Copies of this patent may be obtained for five cents each, by addressing the "Commissioner of Patents, Washington, D. C."

Having described my invention, what I claim is:

1. A comb in which the teeth are formed of unpolished fibrous wood having the 25 fibers extending longitudinally of the teeth and their ends projecting laterally from the teeth to form a brush like surface.

2. A comb having teeth of woody fibrous material in which the free ends of a multiplicity of fibers protrude from the body of the teeth to form a brush like surface. 30

3. A comb in which the teeth are formed of unpolished wood having a multiplicity of integral surface fibers projecting therefrom 35 to form a brush like surface.

In testimony whereof I have affixed my signature in presence of two witnesses.

GEORGE E. SHAW.
